UNITED STATES PATENT OFFICE.

HUGO KÜNZEL, OF COLOGNE-LINDENTHAL, GERMANY.

DESIGN FOR A CASING FOR TOY SHOOTING APPARATUS.

No. 37,831.

Specification for Design.

Patented Feb. 20, 1906.

Application filed November 23, 1905. Serial No. 288,818. Term of patent 7 years.

To all whom it may concern:

Be it known that I, HUGO KÜNZEL, merchant, a subject of the King of Prussia, German Emperor, and a resident of No. 2 Kremenzstrasse, Cologne - Lindenthal, German Empire, have invented a new, original, and ornamental Design for the Casing of a Signaling Toy Shooting Apparatus, of which the following is a specification, reference being had to the accompanying drawings, forming a part thereof.

The nature of my new design is clearly disclosed by the drawings, in which—

Figure 1 is a front elevation of the casing, showing my design; and Fig. 2 is an end elevation thereof.

I claim—

The ornamental design for a casing for a toy shooting apparatus, as shown.

HUGO KÜNZEL.
